UNITED STATES PATENT OFFICE.

FRANCIS R. CLARK, OF BEDFORD, IOWA.

WIRE-SPLICER.

1,075,333.

Specification of Letters Patent. Patented Oct. 14, 1913.

Application filed December 8, 1912. Serial No. 735,780.

To all whom it may concern:

Be it known that I, FRANCIS R. CLARK, a citizen of the United States, residing at Bedford, in the county of Taylor and State of Iowa, have invented certain new and useful Improvements in Wire-Splacers, of which the following is a specification, reference being had to the accompanying drawings.

10 This invention relates to new and useful improvements in wire working tools and more particularly to a wire splicer, the object of the invention being to provide a splicer for coiling the ends of wires around the body portion of the same or another wire or another object, and is more particularly adapted for use in fence building, splicing telephone and telegraph wires and for similar purposes, but may be employed for other

15 purposes.

Another object of the invention is to provide a tool of the above character which will possess advantages in points of efficiency and durability, is inexpensive to manufacture and at the same time is simple in construction and operation.

With the above and other objects in view, the invention consists in the novel features of construction and the combination and arrangement of parts hereinafter more fully described pointed out in the claims and shown in the accompanying drawings in which,

Figure 1 is a perspective view of a wire splicer constructed in accordance with my invention. Fig. 2 is a front elevation and Fig. 3 is a sectional view taken on the line 3—3 of Fig. 2.

Referring more particularly to the drawings, 1 indicates the handle provided at one end with a circular head 2 having a similar shaped opening 8 formed therein. Rotatably mounted within the opening 3 is a circular body 4 having an enlarged head 5 formed upon one end thereof and rotatably mounted within a circular recess 6 formed in the detachable plate 7 secured to one side of the head 2. The plate 7 is provided with a reduced shank 8 which conforms in size to the handle 1 and is detachably secured thereto by means of the screw bolt 9. From this it will be readily apparent that the plate 7 may be quickly and easily removed and the body 4 removed from the handle. The body 4 is provided with a longitudinal groove 10 which is adapted to register with the re-

cesses 11 formed in the plate 7 and the head 2 of the handle. The body 4 is provided adjacent the head 2 with a ratchet portion 12 which is adapted to be engaged by a pawl 13 pivotally mounted upon the handle 1. The body is provided upon one side with a flattened face 14 having a transverse groove 15 formed therein adapted to receive the rib 16 formed upon the gripping member 17 which is secured to the body 4 by means of the screw bolt 18, said screw bolt passing through an elongated opening 19 formed in the gripping member whereby the gripping member will be movably mounted upon the body.

The gripping member 17 is provided at one side with an upstanding ear 20 having a groove 21 formed therein adapted to receive one end of the wire should the same be inserted up through the opening 22 to be twisted about the body portion of the wire. The opening 22 communicates with the groove 21 in which is arranged the end of the wire which is adapted to be twisted around the body thereof. In splicing the ends of two wires, the ends are arranged in parallel relation and placed within the longitudinal groove 10 and the recesses 11, the end of one of the wires is then bent downwardly through the opening 22 and the handle 1 rotated about the other wire so that the end which is bent downwardly through the end 22 will be twisted around the other wire. After the first end has been twisted about the other wire, the device is reversed and the end of the other wire is inserted down through the opening 22 and the handle rotated about the wire so that the second end will be rotated about the body of the first wire forming an extremely strong joint between the ends of two wires.

It will be readily apparent that after the two ends of the wires have been arranged within the longitudinal groove 10 and the recesses 11, a pair of pliers may be used to twist the end of one of the wires about the other wire at one end of the groove. After this has been done, the wire is moved along so that the end of the other wire may be twisted about the first wire, thus eliminating the necessity of turning the handle number 1 around the two wires. It will be understood that either means may be employed for fastening the two ends of the wires together.

From the above it will be apparent that

by the use of my improved splicer, the ends of two wires may be quickly and easily connected together. It will also be apparent that the device is simple in construction, 5 easy to operate and can be manufactured at a comparatively low cost.

While I have shown and described the preferred form of my invention, it will be obvious that various changes in the details 10 of construction and in the proportions may be resorted to for successfully carrying my invention into practice without sacrificing any of the novel features or departing from the scope of the appended claims.

15 What I claim is:—

1. In a device of the character described, the combination with a handle, a circular head formed integral with the handle and provided with a similar shaped opening, a 20 plate secured to the head and provided with a circular recess, a circular body having an enlarged head formed upon one end and arranged within said recess, a ratchet portion formed on said body, a pivoted pawl adapted to engage the ratchet portion whereby turning movement of the handle will rotate the body, said body being provided upon one side with a flattened face having a transverse groove formed therein, a gripping 25 member provided with a rib adapted to engage within said groove, said gripping member being provided with an elongated opening, a screw bolt passing through said opening and engaging with the body whereby the gripping member is adjustably secured to the body, and means for engaging the angularly bent end of a wire whereby the rotation of 30 the handle will twist said end about the body portion of another wire.

ing, and a screw bolt passing through said opening and engaging with the body whereby the gripping member is adjustably secured to the body. 35

2. In a device of the character described, the combination of a handle, a circular head formed at one end of the handle and provided with a similar shaped opening, a plate 40 secured to one side of the head and provided with a circular recess, a circular body member having an enlarged head formed at one end thereof and disposed within said recess, said body member being provided upon one 45 side with a flattened face having a transverse groove formed therein, a gripping member provided with a rib adapted to engage within said groove, said gripping member being provided with an elongated opening, a screw bolt passing through said opening and engaging with the body whereby the gripping member is adjustably secured to the body, and means for engaging the angularly bent end of a wire whereby the rotation of 50 the handle will twist said end about the body portion of another wire.

In testimony whereof I hereunto affix my signature in the presence of two witnesses.

FRANCIS R. CLARK.
